DEVICE FOR MARKING LOOM FILLING BOBBINS

Francis Raymond Race, Rensselaer, N. Y., assignor to F. C. Huyck & Sons, Rensselaer, N. Y., a corporation of New York

Application February 24, 1949, Serial No. 78,090

6 Claims. (Cl. 242—1)

2

1

My invention relates to the textile machinery art and particularly to a device for applying one or more marks on yarn as it is being wound on a winder of the Abbot or revolving type for the purpose of identifying, as a lot, the yarn which is wound at the same time on a plurality of bobbins carried by the winder. While it is the usual practice to mark the yarns on the bobbins as they are rotating in the winder, this is generally done by holding a piece of chalk or a crayon against the yarn.

One of the objects of my invention is to provide a simple, substantially fool-proof device for automatically marking the yarn on the bobbins during the winding thereof. Another object is to provide a device of this character which will be automatically controlled to bring the marking means into contact with the yarn on the bobbin as the bobbin passes by the point where the marking device is positioned and, thereafter, to raise the marking device so that it will not interfere with the movement of those parts of the winder, such as the traversing mechanism, which are disposed between the bobbins. Another object is to provide a device of this character in which the marking means, such as a crayon, will be automatically fed towards the yarn to compensate for wear. A further object is to provide a means cooperating with the yarn and also with the crayon for limiting the feeding of the crayon substantially to that very short interval during which the crayon is disposed over the yarn.

I accomplish these objects by means of the novel elements and the combinations and arrangements thereof described below and illustrated in the accompanying drawings in which—

Fig. 1 is a fragmentary, plan view of so much of a loom filling bobbin winder as is necessary to illustrate the operation of my invention in connection therewith;

Fig. 2 is a side elevation view of the device, as shown in Fig. 1;

Fig. 3 is an enlarged, elevation view of the marking device, with parts broken away, as viewed through the plane 3—3 in Fig. 1;

Fig. 4 is a left hand side view of the device shown in Fig. 3;

Fig. 5 is a section of Fig. 3 in the plane 5—5;

Fig. 6 is a fragmentary, perspective view of the marking device shown in Fig. 3, as viewed from the side and rear thereof; and

Fig. 7 is a fragmentary, side elevation view of the marking device with the parts in a slightly different position from that shown in Fig. 4.

Referring to the drawing—

1 generally represents the winder having the rails 2 and 3 which form a track for supporting the bobbins and the winding mechanism. The rails 2 and 3 are straight at the sides of the machine and the straight portions are connected by curved portions at each end to form a continuous, generally oval shaped track. Low voltage electric motors are shown at 4 which drive shafts connected to the bobbins 5 and, through mechanism (not shown) in the housings 6, also actuate the traversing elements 7 through which the yarns 8 are guided as they are wound on the bobbin to effect an even distribution thereof on the bobbin. The motors are connected to and carried by a chain 9 which is driven by the sprocket 10 through a motor and speed-reducing device 11 in the direction of the arrows shown in Fig. 1.

The foregoing mechanism is well known in the art, and, therefore, I have described only such parts thereof as are intimately associated with my invention.

Referring now more particularly to Figs. 3—7, inclusive, my marking device comprises one or more vertically-disposed, tubular elements such as 12 and 13 which are open at the top and bottom, as shown in Fig. 5, and in which chalk or crayons 14 and 15 are normally free to slide. These tubes are secured at their lower ends in a block 16 which carries the mechanism for controlling the feed of the crayons towards the bobbins 5. In order to insure that the crayons will move freely downwardly towards the bobbins, springs or weights 17 in the tubes 12 and 13 rest on top of the crayons, as best shown in Fig. 5. Thus, it will be apparent that, unless the downward movement of the crayons is restrained in some way, they will fall out of the bottoms of the tubes when not in contact with the yarn on the bobbins.

40 In order to control the downward sliding movement of the crayons in the tubes 12 and 13, I have provided a clutch element for each crayon which is normally in frictional engagement with the crayon and holds it in fixed relation to the tubular element in which it is held but which is adapted automatically to release the crayon when the clutch mechanism is contacted by the yarns on the bobbins as they pass under the crayon.

45 As illustrated in the drawing, each clutch element comprises a piece of comparatively stiff wire bent, as shown, to provide two parallel-disposed portions 18 and 19 and a depending loop portion 20. Each of the portions 18 is mounted 55 to oscillate in a horizontal bearing 21 on one

side of the block 16 near the bottom thereof. The portions 19 which are above the portions 18 are retained within the transversely-extending slot 22 in the block 16 by means of the depending portions 23 of the plate 24 which extend at least partially over the entrance to the slot, as shown in Figs. 4, 5 and 7. The portions 19 of the clutch elements can oscillate freely in the slots 22 towards and away from the tubes 12 and 13, and, within the range of movement of the portions 19, each of the tubes is cut away, as perhaps best shown in Figs. 4 and 5, to expose the crayons to contact with the portions 19 of the clutch elements.

Each of the portions 19 is normally held in frictional engagement with the crayon associated therewith by means of a helical, tension spring 25 cooperating therewith. The depending looped portions 20 of the clutch elements extend downwardly below the block 16 and are adapted to contact the yarns on the bobbins as they pass under the marking device, as shown in Figs. 3-6, inclusive.

When the depending looped portions 20 are not in contact with the yarns on the bobbins, the portions 19 of the clutch elements are held in tight, frictional engagement with the crayons by means of the helical springs 25, as shown in Fig. 7. Bearing in mind that the bobbins are moving in the direction of the arrows shown in Figs. 4-7, it will be apparent that when the yarns on the bobbins strike the portions 20, these portions will be swung counterclockwise in the bearings 18, and the portions 19 of the clutch element will also be swung counterclockwise to the positions shown in Figs. 4 and 5 and out of frictional engagement with the crayons. Thus, the crayons are free to slide downwardly in the tubes 12 and 13 by gravitational action assisted by the weights 17 superimposed thereon so that wear on the crayons is automatically compensated.

Referring now to Figs. 1, 2, 3, 4 and 6, the marking device shown in Figs. 3-7, inclusive, is supported in operative relation to the bobbins on the winder as follows:

The block 16 is attached to an arm 26 by means of screws 27 which cooperate with the threaded holes 28 in block 16. The arm 26 is secured to a shaft 29 which is mounted to oscillate in bearings 30, 31 and 32 in, or secured to, the bar 33 which is supported on the vertical post 34. Also secured to the shaft 29 is the depending lever 35, the lower portion of which is adapted to ride, at times, on the housings 6 (see Figs. 1 and 2). The function of the arm 35 is to maintain the marking device normally raised above the path through which the bobbins on the winder and the parts of the winder disposed between the bobbins pass. Thus, when the lower portion of the depending lever 35 is riding on top of the housings 6, the crayons and the depending looped portions of the clutch mechanism are held above and out of contact with the yarns. As illustrated in Figs. 1 and 2, the depending lever 35 has just dropped off the top of the housing 6 immediately adjacent thereto at the right, at which time a bobbin is positioned immediately below the marking device so that, as the depending lever 35 drops off said housing to the right, the crayons are brought into contact with the yarn, and the looped portions 20 of the clutch mechanism, when they contact the yarn, release the crayons so that they are free to move toward the yarn if they are not already in contact therewith. How-

ever, as soon as the bobbin which is immediately under the marking device, as illustrated in Figs. 1 and 2, passes to the right, the depending lever 35 rides over the next adjacent housing 6 on the left and raises the marking device out of the path of those parts of the winder which are disposed between the bobbins; and, at the same time, the crayons are frictionally engaged by the portions 19 of the clutch mechanism so that they cannot drop out of the tubes 12 and 13.

Since it may be desirable to mark the yarns on the bobbins only when the bobbins are substantially filled, an adjustable stop screw 36 (see Fig. 2) is provided to cooperate with the arm 26 to limit the downward movement of the marking device.

From the foregoing, it will be apparent that, by means of my device, the yarn on each bobbin will have applied thereto, during the winding thereof, one or more circumferential marks which may be in any desirable color or combination of colors so that all of the bobbins which are simultaneously wound will be identified as a lot or group. As the crayons wear, they will be automatically fed towards the bobbins so that such wear will be compensated.

While I have illustrated only two crayons, it is to be understood that either one or more than two crayons may be employed if desired.

While I have described my invention in its preferred embodiment, it is to be understood that the words which I have used are words of description rather than of limitation and that changes, within the purview of the appended claims, may be made without departing from the true scope and spirit of my invention in its broader aspects.

What I claim is:

1. In a bobbin winding device of the type in which a plurality of spaced bobbins having their axes substantially horizontal are moved around in a continuous path simultaneously with the winding thereof; the combination with means for holding a crayon in close proximity to the path traversed by said bobbins, a mounting for said holding means adapting it to move towards and away from said path, whereby to move a crayon held by said means into and out of said path; means cooperating with said holding means for controlling the movements thereof in timed relation to the movements of said bobbins past said holding means to bring said crayon into contact with the windings on said bobbins as they pass said holding means and thereafter to move said crayon out of the zone through which said windings pass, and means cooperating with a crayon when in said holding means and actuated by the windings on said bobbins for effecting a movement of said crayon, relative to said holder, and towards said path to compensate for wear on said crayon.

2. In a bobbin winding device of the type in which a plurality of spaced bobbins having their axes substantially horizontal are moved around in a continuous path simultaneously with the winding thereof; the combination with a tubular element adapted to hold a crayon freely slideable therein and disposed substantially vertically above the path traversed by said bobbins, a mounting for said tube adapting it to move towards and away from said path; whereby to bring the lower end of a crayon projecting from said tube into and out of contact with the windings on said bobbins to apply a mark thereto; means cooperating with said holder for controlling the movements thereof in timed rela-

tion to the movement of said bobbins past said tube to bring said crayon into contact with said windings and withdraw it therefrom, and means cooperating with said crayon for normally holding it in fixed relation to said tube but adapted to cooperate with the windings on a bobbin as it moves past said tube to release said crayon; whereby, when released, said crayon may slide downwardly in said tube automatically to compensate for wear.

3. In a device adapted to apply an identifying mark to yarn being wound on rotating bobbins moving past said device, the combination with a tubular element having its axis disposed towards said bobbins as they pass said device and open at the end thereof adjacent said bobbins, of a crayon freely slideable in said tubular element, means cooperating with said crayon and normally urging it out of the open end of said tubular element towards said bobbins, and means cooperating with said crayon and normally holding it in fixed relation to said tubular element, including means adapted to cooperate with said bobbins as they pass said device for momentarily releasing said holding means to effect a movement of said crayon towards said bobbins; whereby, automatically to compensate for wear on said crayon.

4. In a device adapted to apply an identifying mark to yarns being wound on rotating bobbins moving past said device, the combination with means adapted to carry a crayon with the end thereof in contact with the yarns on said bobbins as they pass said device, of means cooperating with said crayon and normally urging it towards said bobbins relative to said carrying means, and means cooperating with said crayon for normally holding it in fixed relation to said carrying means but adapted to cooperate with the yarns on said bobbins as they pass said device for momentarily releasing said holding means to effect a movement of said crayon towards said yarns to compensate for wear on said crayon.

5. In a device adapted to apply identifying marks to yarn being wound on rotating bobbins moving past said device, the combination with a plurality of tubular elements having their axes disposed towards said bobbins as they pass said device and open at the ends thereof adjacent said bobbins, of crayons freely slideable in said ele-

ments, means cooperating with said crayons and normally urging them out of the open ends of said tubular elements into contact with the yarns on said bobbins as they pass said device, means cooperating with said crayons and normally holding them against sliding movement in said elements, and means cooperating with said bobbins as they pass said device for momentarily releasing said holding means to allow said crayons to slide towards said bobbins to compensate for wear on said crayons.

6. In a bobbin winding device, the combination with means for holding a plurality of bobbins with their axes substantially horizontal and in laterally-spaced relation to each other, of means for rotating said bobbins to wind yarns thereon, means for simultaneously moving said bobbins and said rotating means around a closed path, a crayon for applying a mark to the yarns on said bobbins, a holder for said crayon in which said crayon is free to slide downwardly by gravity disposed above the path traversed by said bobbins, a mounting upon which said holder is movable up and down to bring the end of said crayon into and out of contact with the yarns on said bobbins, means cooperating with said holder in timed relation to the movement of said bobbins in said path for moving said crayon into contact with the yarns on said bobbin as it passes beneath said holder and substantially immediately thereafter raising said crayon out of the path traversed by said bobbins, and a clutch cooperating with said crayon for normally holding it in fixed relation to said holder, including means adapted to cooperate with the yarn on a bobbin when beneath said holder for releasing said clutch to allow said crayon to move downwardly toward said yarn to compensate for wear on said crayon.
